UNITED STATES PATENT OFFICE

HAROLD J. GOSS, OF NASHUA, NEW HAMPSHIRE, ASSIGNOR TO THE INTERNATIONAL PAPER BOX MACHINE COMPANY, OF NASHUA, NEW HAMPSHIRE, A CORPORATION OF MAINE

MACHINE FOR APPLYING STRIPS TO BLANKS

Application filed November 15, 1929. Serial No. 407,470.

This invention relates to the production of adhesively united blanks and strips, and has particular reference to the preparation of blanks for paper boxes with strips of thin material secured to predetermined areas thereof.

In the manufacture of paper boxes, it is frequently desirable that certain portions thereof shall have strips of paper adhesively secured thereto and, in the interest of economy in the cost of production of the boxes, it is preferable that the strips shall be applied to the blanks before such blanks are converted to box form either as set-up boxes or flat folded boxes, or for making articles other than boxes. And it is important that the strips shall be accurately located when affixed to the blanks, not only as to lateral position thereon but also as to longitudinal position, with no end portions of the strips projecting beyond the edges of the blanks unless for some boxes such projection of the strips is desired.

The object of the present invention is to provide a machine capable of rapidly effecting the production of articles such as box blanks each having one or more strips of paper or other desired material adhesively connected to one or more predetermined areas thereof for such purposes as, for instance, is explained in Letters Patent No. 1,634,073 issued June 28, 1927, to E. W. Labombarde.

With the above stated object in view, the invention consists in the construction and combination of parts substantially as herein-after described and claimed.

Of the accompanying drawings which illustrate so much of one embodiment of the invention as is necessary for an understanding of the same:

Figure 1 is a side elevation, partly in section on line 1—1 of Figure 2, of that portion of the complete machine embodying the present invention.

Figure 2 is a plan view of the same but omitting some details.

Figure 3 represents a detail section on line 3—3 of Figure 2.

Figures 4, 5 and 6 are detail views, on a smaller scale than Figure 1, illustrating suc-

cessive steps or points of the progress of a blank through the machine and the application of a strip thereto.

Figure 7 is a plan view of one type of blank having strips secured thereto by mechanism 55 such as illustrated in the other views.

Similar reference characters indicate similar parts or features in all of the views.

Portions of the frame of the machine are illustrated at 12. One of the side members of the frame is omitted from Figure 2. In the complete machine, as will be readily understood without an illustration thereof, the omitted side member is a duplicate of the illustrated member. The parts illustrated 60 are sufficient to apply a single strip to a blank, and the machine may be so employed. But when two strips *a* (see Figure 7) are to be applied to a blank *b*, the machine includes two of the mechanisms illustrated by Figures 1, 2 and 3, such two mechanisms being 70 duplicates and side by side. For present purposes it is unnecessary to illustrate both. Of course in such machine the two side members of the frame are connected by suitable 75 tie rods one of which is illustrated at 13.

By suitable feeding mechanism such as is well-known in box-making machinery, blanks are delivered in timed spaced relationship, by carrying chains 14 having pushing lugs 80 15, to the mechanism included in the present invention. The delivery end of each chain is mounted on a sprocket 16 carried by shaft 17. For the reason hereinbefore explained, Figure 2 illustrates but one of the usual pair 85 of chains.

A glue box 18 (Figs. 2 and 3) is supported by a carriage mounted at one end on a slotted cross bar 19 to provide for lateral adjustment. Rotating in the glue box is a roll 20, 90 the coating of glue thereon being controlled by a customary "doctor" roll 21. Such coating is transferred by a roll 22 to the member which applies glue to a blank fed along below it, said member comprising a disk 23 having a raised peripheral portion hereinafter referred to as the gluing arc 24. The short shafts of said disk and rolls are supported by the carriage 25 which also supports the glue box.

Below the disk 23 is a roll 26 carried by shaft 27 having a sprocket connected by a chain 28 with the shaft 17. Another sprocket of the shaft 27 is engaged by a drive chain 29. The gearing connecting the shafts of the 5 gluing mechanism is illustrated as a group at 30.

The strip *a*, usually of paper, is supplied from a roll enclosed in a reel 31 supported by a fixed upright 32 the lower end of which is secured at 33 to a casting 34 which is mounted on the cross bars 35 and laterally adjustable thereon. Said casting is provided with a pair of strip-guiding rolls 36, 37, one above 10 the other, and with another pair of rolls 38, 39, side by side. And rising from the casting is an upright 40. A roll 41 supported by said upright may be set at a greater or lesser height by means of the slot in the upright.

Pivoted at 42 to the casting 34 is a rocker arm 43 having a roll 44 which is acted upon by a cam 45 carried by a shaft 46. A spring 47 tends to keep the rocker raised. A rubber block 51 secured to the under side of the rocker arm coacts with one of the bars 35 to grip 20 the strip *a* as presently described.

The end of the rocker carries a strip weakener 52 preferably a toothed blade. When the rocker is depressed, the member 52 so acts 30 on the strip *a*, as by forming a line of perforations across it, that the strip can be severed at that point by a pulling action effected by mechanism yet to be described. The elastic block 51 at the same time so grips the strip 35 against the bar 35 that the described action of the weakener 52 will not draw the strip along.

Extending through the casting 34 is a rock shaft 53 having an arm 54 projecting from it over the path of the strip *a*, and carrying a 40 yieldable presser 55 which coacts as herein-after described with a plate 56 that is supported by the casting 34. The rock shaft 53 (Figs. 2 and 3) has another arm 57 provided 45 with a roll 58 that is acted upon by a cam 59 carried by the shaft 17. A spring 60 connects the arm 57 with an arm 61 fixed to the tie rod 13, said spring having such strength as to cause the presser 55 to bear strongly on 50 the strip *a* and grip it firmly on the plate 56 at the stated times hereinafter described.

From the mechanism so far described the strip *a*, and also intermittently advanced blanks, pass over a lower roll 62 and under 55 an upper roll 63, said two rolls being so spaced that there can be no pinching of the strip alone between them. That is, there must be a blank *b* as well as the strip *a* between said two rolls in order to cause any 60 feeding or pulling action by said two rolls.

The roll 63 has two recesses in its periphery, one wider than the other, as illustrated respectively at 64, 65, the purposes of which will be explained during the description of 65 the operation of the machine.

The roll 63 is constantly driven through the medium of any suitable gearing not necessary to illustrate, such driving being in proper timed relationship to accord with the timing of action of the pushing lugs 15.

The blanks and the overlying strip thereon issuing from between the rolls 62, 63, have a pulling action imparted thereto by a pair of rolls 66 (Figs. 1, 4, 5 and 6) which, as well as the rolls 62, 63, in the operation of 75 the machine, have a higher peripheral speed than the speed of travel of the pushers 15.

To prevent the strip *a* from having any retrograde movement relatively to the plate 56, a spring detent 67 is provided (Fig. 1), said 80 detent being secured to the casting 34 and having its free edge bearing on the strip.

When the mechanism is constructed to simultaneously apply a plurality of stripes *a* to each passing blank (see Figure 7), the 85 mechanism illustrated by Figures 1 and 2 is duplicated, and one or both of such mechanisms is so mounted as to be laterally adjustable to suit the width of the space between the two parallel strips. To enable the mechanism, whether single or duplicated, to apply strips of greater or lesser lengths to blanks of corresponding length, the roll 23 is removable and replaceable so that the machine may have a roll provided with a projecting gluing 90 arc 24 the length of which arc will correspond with the length of the section of the strip *a* that is to be applied to the blank. For the same reason the roll 63 is removable and replaceable so that one having properly 100 spaced recesses 64, 65, may be employed. And the roll 41 is adjustable to proper vertical position to suit the length of the strip sections to be applied to the blanks.

When the machine is prepared for operation, the strip *a* is threaded as illustrated by Figure 1, with its free end extending between the rolls 62, 63, (Fig. 4), and with the guide roll 41 located at such height that the length of the strip from the weakener 52 to the nip of the rolls 62, 63, equals the length of the surface of the gluing arc 24. This is when the machine is to be used to apply strip sections to blanks throughout the lengths of said sections. If it be desired that the applied strip sections shall have free or unsecured ends, a roll 23 will be employed in the machine which roll will have a gluing arc of less length than the strip sections that are to be successively applied to blanks. With the last-mentioned arrangement, the stripes of glue that will be applied to the blanks will be shorter than the strip sections *a* and therefore the ends of the latter will not be stuck to the blanks.

When the machine is started, nothing happens until a blank is fed by the pushers 15, excepting that the weakener 52 and the gripper 55 will be oscillating. The strip *a* will not be advanced because the space between 125

the rolls 62, 63, exceeds the thickness of said strip. But when a blank *b* is pushed along by the lug 15 or its equivalent, and the front edge thereof arrives between the rolls 62, 63, 5 under the strip (Fig. 5), the combined blank and strip are gripped and drawn along and pass to the nip of the pulling rolls 66 (Fig. 6). Since the arriving blank just mentioned has had a stripe of glue applied to its upper surface by the gluing arc 24, the strip and blank 10 are adhesively united as they pass along between the rolls.

The timing is such that the presser 55 is raised during the first part of the pulling 15 operation just described, but is lowered to grip the strip after the last preceding line of cross perforations made by the weakener 52 has passed said presser, thereby holding the strip at the rear of its weakened point so 20 that the section of the strip which is on the blank will be pulled away from the remaining portion of the strip, the weakening of the strip enabling this to be done. And said remaining portion will be stationary until the next blank 25 reaches the position illustrated by Figure 5 and results in a pulling action being imparted to the strip and blank by the rolls 62, 63.

The timing is also such that when the breaking away of a strip section has been effected as just described, the end of the now 30 stationary strip will be in the position illustrated by Figure 4, just reaching the space between the rolls 62, 63. And when the next blank arrives with its front edge between 35 said rolls, the recess 64 of the roll 63 will arrive above the roll 62. The said recess 64 is to enable the front edge of the blank to reach a position slightly beyond the vertical plane of the axes of the two rolls 62, 63, before an 40 actual pulling nip or grip is effected by the said rolls, thereby providing for registration of the front edge of the blank with the previously located front end of the strip *a*. Said strip has been stopped by the action of 45 the gripper 55 with its front end slightly beyond the vertical plane of the axes of the two rolls.

The gripping action referred to occurs at 50 the instant that the rear edge of the blank is leaving the nip of the rolls 62, 63, and simultaneously therewith the recess 65 in the roll 63 arrives above the rear edge of the blank and its applied strip section. As the blank and 55 strip section have now reached the rolls 66, the latter can, and do by their pulling action, separate the applied section of the strip from that portion which is then to remain stationary to await the arrival of another blank. 60 If there were no recess 65, the nip of the rolls 62, 63, would pull the strip too far and possibly cause another parting of it at a wrong point. But the recess 65 effects a releasing 65 of all pulling action by the rolls 62, 63, at the proper moment to let the rolls 66 do the pull-

ing that is necessary to part the strip accurately.

From the description of the machine which has now been given, it will be understood that the blanks are caused to travel by the pushers 15 and while so travelling receive stripes of adhesive from the gluing arc 24, and that the strip material *a* is weakened at spaced intervals by the blade 52 so that a pulling action 20 can successively detach sections therefrom, and that the strip material is drawn along and pressed on the glue stripes of the successively passing blanks, thereby effecting the rapid production of such articles as illustrated by Figure 7, or any other blanks requiring the adhesive application thereto of accurately located strips.

Having now described my invention, I claim:

1. A machine for affixing sections of strip material to blanks, comprising means for causing blanks to travel, means for applying adhesive stripes to the blanks, means for weakening the strip material at spaced intervals to provide strip sections, means for applying the strip material to the adhesive stripes of the blanks, and means rendered effective by the combined thickness of the blank and strip for parting the strip material successively at its weakened points.

2. A machine for affixing sections of strip material to blanks, comprising means for causing blanks to travel, means for applying adhesive stripes to the blanks, means for weakening the strip material at spaced intervals to provide strip sections, means for pressing the strip sections successively on the adhesive stripes of the travelling blanks, and means controlled by the combined thickness of the blanks and strip sections for exerting a pulling action on said combined blanks and strip sections.

3. In a machine having means for causing blanks to travel and means for successively detaching sections of predetermined length from a strip, means for bringing the strip sections and blanks into superimposed relationship, and means for applying stripes of adhesive to those areas of the blanks which are to receive the strip sections, the means for detaching said sections from the strip including pulling members spaced to act only when a blank and strip are between them.

4. In a machine having means for causing blanks to travel and means for successively detaching sections of predetermined length from a strip, means for bringing the strip sections and blanks into superimposed relationship, and a rotary gluing arc in position to successively apply stripes of adhesive to the travelling blanks before the strip sections are in contact with the blanks, the means for detaching said sections from the strip including pulling members spaced to act only when a blank and strip are between them.

5. In a machine of the character described, a blank carrier, means for applying glue to the blanks, an intermittently acting strip weakener, means for drawing a strip past said weakener and pressing it on the blanks, said drawing means including pulling members spaced to act only when a blank and strip are between them, and guides for the strip intermediate the weakener and said strip-drawing means, one of said guides being adjustable to vary the length of a strip section reaching from the weakener to the strip drawing means.
6. In a machine of the character described, a blank carrier, means for applying glue to the blanks, an intermittently acting strip weakener, rolls for drawing a strip past said weakener and pressing it on the blanks, said rolls being spaced to act only when both a blank and strip are between them, and guide rolls for the strip intermediate the weakener and the strip-drawing rolls, one of said guide rolls being adjustable to vary the length of a strip section reaching from the weakener to the strip-drawing rolls.
7. A machine for affixing sections of strip material to blanks, comprising means for causing blanks to travel, means for applying adhesive stripes to the blanks, a rocker having a blade for acting on the strip material at spaced intervals to provide strip sections, and means for pressing the strip sections successively on the adhesive stripes of the travelling blanks, said pressing means including pulling members spaced to act only when a blank and strip are between them.
8. A machine for affixing sections of strip material to blanks, comprising means for causing blanks to travel, means for applying adhesive stripes to the blanks, a rocker having a blade for acting on the strip material at spaced intervals to provide strip sections, a gripping member carried by said rocker to hold the strip during the action of said blade, and means for pressing the strip sections on the adhesive stripes of the travelling blanks, said pressing means including a pulling member spaced to act only when a blank and strip are between them.
9. A machine for affixing sections of strip material to blanks, comprising means for causing blanks to travel, means for applying adhesive stripes to the blanks, means for weakening the strip material at spaced intervals to provide strip sections, means for pressing the strip sections successively on the adhesive stripes of the travelling blanks, rolls for exerting a pulling action on the combined blanks and strip sections, said rolls being spaced to act only when both a blank and strip are between them, and a gripper to hold the strip material during the operation of said pulling rolls.
10. A machine for affixing sections of strip material to blanks, comprising means for causing blanks to travel, means for applying adhesive stripes to the blanks, means for weakening the strip material at spaced intervals to provide strip sections, and means for pressing the strip sections successively on the adhesive stripes of the travelling blanks, said pressing means comprising a pair of rolls permanently spaced to avoid having any pressing action on the strip material alone.
11. A machine for affixing sections of strip material to blanks, comprising means for causing blanks to travel, means for applying adhesive stripes to the blanks, means for weakening the strip material at spaced intervals to provide strip sections, and means for pressing the strip sections successively on the adhesive stripes of the travelling blanks, said pressing means comprising a pair of rolls permanently spaced to avoid having any pressing action on the strip material alone, one of said rolls being peripherally recessed.
12. A machine for affixing sections of strip material to blanks, comprising means for causing blanks to travel, means for applying adhesive material to the blanks, means for weakening the strip material at spaced intervals to provide strip sections, and means for pressing the strip sections successively on the adhesive stripes of the travelling blanks, said pressing means comprising a pair of rolls permanently spaced to avoid having any pressing action on the strip material alone, one of said rolls having two recesses in its periphery, one recess being wider than the other.
13. A machine for affixing sections of strip material to blanks, comprising means for causing blanks to travel, means for applying adhesive stripes to the blanks, means for weakening the strip material at spaced intervals to provide strip sections, a pair of permanently spaced rolls for pressing the strip sections on the blanks, and a pair of rolls for exerting a pulling action on the combined blanks and strip sections.
14. A machine for affixing sections of strip material to blanks, comprising means for causing blanks to travel, means for applying adhesive stripes to the blanks, means for weakening the strip material at spaced intervals to provide strip sections, a detent for preventing backward movement of the strip material, and means for pressing the strip sections successively on the adhesive stripes of the travelling blanks, said pressing means including pulling members spaced to act only when a blank and strip are between them.
- In testimony whereof I have affixed my signature.
- HAROLD J. GOSS.
